UNITED STATES PATENT OFFICE.

HENRY C. NATERMAN, OF LOS ANGELES, CALIFORNIA.

RESILIENT PACKAGE-HOLDING DEVICE.

Application filed December 24, 1925. Serial No. 77,474.

A main object is to provide a simple package holding device formed of a single piece of spring wire, that is of simple construction and which with the packages of materials 5 secured thereto may be quickly mounted within the central opening of hollow paper rolls without mutilating or injuring the paper of the roll in the slightest manner.

A further object is to provide a device that 10 is maintained within the opening of a paper roll solely by its resiliency.

Further objects and advantages will be apparent from the following specification, reference being had to the appended drawings, in which:

Fig. 1 is a perspective detail view partly in section, of one end of a roll of roofing paper, the package holding device being shown in position.

Fig. 2 is a longitudinal section through one end of a paper roll showing the device mounted therein supporting the packages of materials.

Fig. 3 is an end view of a paper roll showing the device in position.

Fig. 4 is a side elevation of the device in open position before insertion within the roll opening.

Fig. 5 is a diagrammatic view showing the 30 method of inserting a holder device carrying packages within a paper roll.

In the manufacture of paper roofings, a heavy paper is employed that is thoroughly saturated in a tar or asphalt compound to 35 water-proof the same. After the paper has been saturated it is formed into rolls of approximately fifteen (15) inches in diameter with a cylindrical opening therethrough of about three and one-half (3½) inches in 40 diameter. This central opening in each roll has been employed for holding a can of cement and a package of nails used by the roofing operators when laying a roof. It has been customary when the paper has been 45 rolled to insert the packages of cement and nails therein and then seal the ends with a flat piece of waste roofing, binding the same thereto with "cheese cloth," a paper finishing end being pasted over the cloth. This 50 method of confining the cement and nails within the hollow rolls not only consumes a great deal of time and labor, but oftentimes the weight of the cement and nails will accidentally force through the closures during 55 the handling of the rolls.

By means of my device it will not be

necessary to seal the open ends of hollow paper rolls, the resilient package holding device securely holding the packages against dislodgement during the handling of the 60 rolls, and at the same time economize materially in time and labor in the placement of packages within the rolls.

Referring now more particularly to the drawings, and especially to Figs. 1 and 4, the 65 device 5, is preferably formed of spring wire of a relatively heavy gauge to insure sufficient resiliency to prevent a dislodgement of the device after it has been mounted within the roll.

In the formation of the device 5 the wire is bent upon itself in equal lengths to form main body portions 6, 7, the central bent portion forming a spring loop 8, the upper ends of each of said body portions are then bent 75 inwardly at substantially right angles to said body portions, and the extreme ends are further bent in substantially circular loops 9 disposed in opposite directions to each other in order to maintain the packages 80 supported by the device against accidental displacement should the roll be placed on end with the loops disposed downwardly.

In order to form a support for containers carried by the device within the opening of 85 the roll, the body portions 6, 7, are bent at right angles directly above the ends of the spring loop 8 to form ledges 12, 13, upon which one of the containers rests when the 90 device is inserted within the roll.

The method of mounting the device in the central opening of a paper roll is extremely simple, the operator first presses the body portions 6, 7, of the device towards each other and at the same time inserting the 95 spring looped end into one end of the roll opening (see Fig. 5), in order to hold the body portions in compression. A can of cement 16 and a paper nail container 17, are then inserted within the holder, the device with the packages then being forced 100 downwardly into position midway between the ends of the roll, as shown in the various views of the drawing.

From the above it will be clear that the 105 packages of materials will be held firmly within the roll opening solely by the resiliency of the holder device, and as the looped ends 9 on the upper ends of the body members 6, 7, engage one of the material containers no accidental displacement of the 110 same can occur. The spring loop 8 of the

device will afford a convenient hand-hold for enabling a workman to readily withdraw the holder and its packages of materials from the roll when desired.

5. What I claim is:

1. A device of the class described comprising a single length of spring wire bent upon itself substantially mid-way of its ends to form a spring loop at its bent portion, the unattached ends of said wire being bent inwardly toward each other to form package stops.

2. A device for holding packages in position within hollow rolls comprising a single length of spring wire bent upon itself at its middle portion to form spring wall gripping arms for the reception of packaged articles therebetween, the ends of said arms being bent towards each other to form stops or 20 supports for said articles.

3. A new article of manufacture comprising a single length of spring wire bent upon itself to form a spring loop at its bent portion and spaced apart, the ends of said wire 25 being bent towards each other to form stops

for packaged articles when disposed between the bent portions of the wire, and seats for supporting packaged articles formed above the spring loop.

4. A new article of manufacture comprising a single length of wire bent upon itself to form a pair of spring arms, the ends of said wire arms being bent at substantially right angles to said arms and being oppositely disposed, said bent ends forming engaging and supporting tongues for packaged articles disposed therebetween.

5. A device for holding packages in position within hollow rolls comprising a spring wire bent into looped form and spaced apart, the ends of said wire being bent inwardly towards each other to form stops or supports for encased materials, and transverse seats formed on said device above its looped portion.

In witness that I claim the foregoing I have hereunto subscribed my name this 18th day of December, 1925.

H. C. NATERMAN.
